UNITED STATES PATENT OFFICE.

HENRY C. PORTER, OF CHICAGO, ILLINOIS, ASSIGNOR OF ONE-HALF TO THE
OWEN H. FAY LIVERY COMPANY, OF SAME PLACE.

DESIGN FOR A BATTERY-PLATE SEPARATOR.

SPECIFICATION forming part of Design No. 31,315, dated August 1, 1899.

Application filed July 1, 1899. Serial No. 722,604. Term of patent 7 years.

To all whom it may concern:

Be it known that I, HENRY C. PORTER, a citizen of the United States, residing at Chicago, in the county of Cook and State of Illinois, have invented a certain new and useful Design for a Battery-Plate Separator, of which the following is a specification.

My design is illustrated in the accompanying drawings, in which—

16 Figure 1 represents a perspective view of a separator embodying my design. Fig. 2 is a side elevation thereof; and Fig. 3 is a vertical section on the line 3 3 of Fig. 2, looking in the direction indicated by the arrows.

15 The leading feature of my design consists of a frame composed of three parallel bars rectangular in cross-section and connected at one end thereof by a rectangular cross-bar of less thickness than the parallel bars and 20 mortised into the ends of the parallel bars, so that the outer edge of the cross-bar lies flush with the ends of the parallel bars.

25 Referring now to the drawings, my separator consists of three parallel bars A, which are rectangular in cross-section, all of said bars being of like dimensions as to length,

breadth, and thickness. Each of said bars is notched or mortised at one end, removing a thickness equal to about one-third the thickness of the bar, and into these notches is 30 fitted a rectangular cross-bar B, which has a thickness equal to about one-third of its width and snugly fits the mortises in the ends of the bars. This arrangement of the members of the separator gives to the same in side 35 elevation a comb-like appearance, in end elevation the appearance of a single bar, while in plan or section the bars appear to be connected at one end by a centrally-located narrow strip of less thickness than the thickness 40 of the bars. It will thus be seen that my design for a battery-plate separator has a characteristic and distinguishing appearance.

Having thus fully described my invention, what I claim, and desire to secure by Design 45 Letters Patent, is—

The design for a battery-plate separator, substantially as herein shown and described.

HENRY C. PORTER.
